UNITED STATES PATENT OFFICE.

LEE P. HYNES, OF ALBANY, NEW YORK, ASSIGNOR TO CONSOLIDATED CAR-HEATING COMPANY, OF ALBANY, NEW YORK, A CORPORATION OF WEST VIRGINIA.

ELECTRIC HEATER AND ITS MODE OF MANUFACTURE.

Application filed January 26, 1922. Serial No. 531,956.

To all whom it may concern:

Be it known that I, LEE P. HYNES, a citizen of the United States, residing at Albany, in the county of Albany and State of New York, have invented certain new and useful Improvements in Electric Heaters and Their Mode of Manufacture, the following being a full, clear, and exact disclosure of the one form of my invention which I at present deem preferable.

For a detailed description of the present form of my invention, reference may be had to the following specification and to the accompanying drawings forming a part thereof, wherein—

Fig. 1 is a side elevation partly in section of my heater;

Figs. 2 and 3 show the terminal for the coil;

Fig. 4 illustrates the mode of manufacture;

Fig. 5 shows the heater coil as a separate article of manufacture;

Figs. 6, 7, 8, 9 and 10 show modifications.

My invention relates to certain improvements in the heater shown in my application of October 18th, 1921, Serial No. 508,542, wherein a tubular shell of metal is rolled or pressed longitudinally into a smaller ribbed tube and contains a parallel inside lining tube of refractory insulation in which the heating coil lies closely. I have now devised a much better form of end-seal and terminal-connector for such heater while I also make a better article by first shaping the metallic shell and then, while the lining tube is inside of it, passing it between two deeply grooved rollers whereby the edges of the roller grooves draw the metal in around the lining on each side. The lining tube is thus gripped by and retained in place inside the shell while the coil is being inserted or threaded through it. Then the coil lies therein so loosely that it may readily be pulled out and replaced. This supplementary treatment also insures a more intimate association of the tube and shell, and hence a better transmission of heat to the latter.

I also make the heater coil a separate article of manufacture available for replacements, by providing it with permanent terminals of a novel kind between which a predetermined length of wire is included to

insure against overheating and destruction of the coil.

Referring to the drawing, 1 represents the steel tube, originally of plain cylindrical form, but for the greater part of its length compressed or rolled laterally until it has assumed the form of a tube of about half the original diameter with two flat flanges or ribs projecting radially therefrom 180 degrees apart. These flanges are shown at 3, 3 and are of a double thickness of sheet metal and are formed by the surplus metal of the original tube over what is required for the smaller tube. The two ends of the tube are left of the original size and form, but have a screw thread 2 rolled or pressed in them.

Inside the central tube of the shell and in heat conducting proximity thereto there is extended a lining 4 of refractory insulation formed in a series of short sections abutting—not telescoping into—one another. Inside of the lining is the heating coil 5. This heating coil as a distinct article of manufacture is shown in Fig. 5. To each end of the coil is attached a rod or stem 6 of metal by the following means:—On the end of rod 6 is screwed a ferrule, or enlargement, 16, shown on a greater scale in Figs. 2 and 3. In the outer surface of ferrule 16 a helical groove 19 is scored and several of the end turns of coil 5 are laid in this groove. Then the ferrule is swaged down compressing the edges of groove 19 on the wire therein, leaving the outside appearance of the ferrule as shown in Fig. 3. This expedient has manifold merits. The swaging produces a perfect electrical contact between the ferrule and the wire of the coil. It does not cause undue stress on the wire as does a twisted joint. It is mechanically strong and permanent and cannot work loose. It is not affected by heat as a soldered joint is, while some resistant heater-wire does not solder well, even if the heat were not too great; but in most cases the operation of the heater gives a temperature too high for a soldered joint. It is also neat and substantial in appearance which is important, since the coils are sold separately for replacements, and it is also inexpensive.

Furthermore by including between the permanent terminals a predetermined length of wire I insure the use at all times of a

correct length of coil, there being otherwise danger of a too short wire being used, the coil being easily extended by drawing it out, with the result of overheating and destruction of the coil, since the correct length can only be ascertained by accurate resistance measurements and computations which it is not practicable for the ordinary user of the coil to make. Since the coil is so elastic longitudinally, its length at any moment gives no accurate idea of the length of wire it contains. With a detachable terminal a considerable amount of wire might be cut or broken off and the terminal reconnected without causing any perception of the loss by the appearance of the coil. If then put in service the coil would overheat by reason of its loss of length and consequent loss of resistance. This is prevented by making the coil a complete unit in itself with permanent terminals between which a predetermined length of wire is included. In addition I provide a flattened enlargement 13 on one or both of the shanks of the stems 6 whereon are stamped appropriate data to identify the coil and prevent its being used in an improper situation. The flattened space on the shank is also of value in assembling the heater, as will be hereinafter explained, while the shank is made long in order to keep the heat away from the insulating seal and the metal parts carried thereby—in particular from the insulation of the outside lead-wire 21 which is not likely to be of heat-proof quality. The length of the stem 6 (which is also of low heat-conducting metal) should be such that such heat as there may be at the end of the coil will be conducted out laterally through the lining 4 to the shell 1 rather than along stem 6. Moreover, I prefer to secure the stem 6 in the ferrule 16 with a fusible solder that will melt at a determined degree of heat. Since the coil is under tension the melting of the solder will release the coil and suddenly break the circuit by the separation of the ferrule and the stem 6. This fusible solder is shown at W in Fig. 9. Each stem 6 is screwed into a metal block or insert 8 that is tightly set into an insulating bushing 9 which, in turn, is screwed into or locked in the end of the metallic shell 1. The outer end of insert 8 is countersunk at 20 and in the bottom of the countersink is the screw hole for binding-screw 10 by which the outside lead-wire is connected to the insert. The countersink 20 allows the screw to be centered and engaged with the insert independently of the screw thread which it subsequently engages. The bushing 9 is preferably of molded refractory material and is provided with a shoulder 11 which abuts against the end of the shell 1 and seals the screw joint. In its outer end is a screw threaded circular recess or opening 22 in

which a perforated plug 15 may be screwed if desired. In the bottom of said recess 22 is a square or polygonal depression 12 for receiving a socket wrench to screw the bushing in the shell 1. Since this square hole or depression is at the bottom of the recess 22, liability of splitting the bushing when screwing it into the shell is materially limited. Since replacement of coils is a necessary practice in the manufacture and use of heaters of this kind, the features I have described become of large importance in rendering the heater available for practical service, especially to persons more or less inexpert in electrical matters. 80

Fig. 4 illustrates the aforesaid supplementary treatment of the shell after it has been first rolled or pressed into shape and the lining 4 inserted. In this Figure 17 and 18 indicate rolls with deep grooves between which the tube is passed. In this operation the edges of the roller grooves draw in the metal tightly around the lining 4, the walls of the flanges 3, 3, being left slightly separated to permit said drawing-in action. 90 This avoids crushing of the lining and secures the lining in the shell sufficiently to maintain it in the shell while the coil is thrust, or threaded, through it. 85

The mode of assembling the aforesaid parts is as follows: Assuming the lining 4 is in place in the shell 1, the coil 5, having both of its permanently connected terminals 6 secured thereto, one of said terminals is first screwed into the insert 8 of one bushing 9. Then the opposite end of the coil with its attached terminal is inserted in the lining with a cord or wire secured to it temporarily and the bushing 9, now attached to the rear end of the coil, is screwed into the shell by a socket wrench in the polygonal depression 12. At the other end of the shell the stem 6 of the inserted coil may be pulled out by said cord or wire and gripped by pliers so that its insert 8 can be screwed on it before its bushing 9 is screwed into the shell. The flat place 13 allows the stem to be held without rotating in the pliers. Prior to screwing said second bushing into the shell it may be turned reversely a few times putting a slight reverse twist in the coil which is subsequently untwisted when the bushing is screwed home on the shell. The coil is thus left in its normal condition. Moreover, this normal condition of the coil is a condition of tension produced by drawing its loose end out to secure it to the corresponding insert. The result is that, in the event of a breakage of the coil, due for instance to a suddenly applied high voltage, the severed ends snap back and instantly rupture the arc formed by the break. That action is similar to the circuit-breaking action above described which occurs when the fuse between ferrule 16 and stem 6 is melted 105 110 115 120 125 130

by heat. By this means the accident aforesaid, which would otherwise cause a violent explosion and report, becomes hardly perceptible.

- 5 By virtue of the easy placement and replacement of the coil, it becomes possible to provide one standard shell and lining for nearly all types and sizes of heater. These standard shells may be kept in stock together with a variety of coils for different voltages and current values, as stamped on the marker-plate 13. Then the user or retailer can insert any desired coil in a standard shell. Heretofore the electric heater 10 trade has dealt only in completed heaters. That practice is changed by my invention and the electric heater business may now be largely in shells and coils which I have made separate articles of manufacture.
- 20 In Fig. 6 I have shown in place of the external wire 21 an adapter-plate 23, having its lower end bent over and connected to the insert 8 aforesaid by the binding screw 10. The end recess in bushing 9 may, if desired, 25 be filled with a plastic material 25, or may be left open. The plate 23 is shown as bolted to a bus-bar 24. This involves no structural change in the heater itself and illustrates its capacity for service under different 30 circumstances. In this case a number of heaters may be similarly connected to the bus-bar 24, a gain in output of heat being secured by multiplying the standard heater units rather than by increasing the size of 35 the heater itself.

In Fig. 7 I have shown the heater shell as provided with local insulation which may be in the form of rings 28 of molded material surrounding the tubular ends of the 40 shell. For this purpose the threads on the shell are replaced near the outer end with a cylindrical seat for the ring having flanges on either edge to retain the ring in position thereon. The ring may be used as the 45 means for supporting the heater as appears in the figure. The entire bracket may be of insulation if desired and the rings 28 may be square or of any other shape. Since the ring 28 is a permanent part of the heater 50 applied at the natural point of support, the heater will normally be mounted so as to insulate the shell as well as the coil, whereby in the event of an accidental connection between the coil and shell the current in the 55 coil will not escape.

In Fig. 8 I have shown a heater shell in the form of a bendable metallic tube 26. This tube may be of soft copper or other flexible or bendable material but I prefer 60 to construct it of overlapping helical plates *a* and *b*. Inside of the tube is the refractory lining formed of short sections 4*, 4* which are of such shape that they may assume a slightly angular relation to one another as the tube assumes a bent or curved

position. To each end of the flexible tube is secured a short rigid pipe 27 wherein is contained the bushing 9 such as I have already described. Within the lining aforesaid is the heating coil with its connected 70 stem 6 as heretofore explained.

In Fig. 9 the stem 6 is connected to ferrule 16 by a fuse *W*, as heretofore mentioned. In the event of the fuse melting and the coil itself acting to separate 16 and 6 the arc will 75 be formed between the terminal 16 and the stem 6 and will not affect the wire of the coil, which, as aforesaid, is swaged in the terminal 16. In this case I add a refractory annular tip to the ferrule 16 to help extinguish 80 the arc.

What I claim as new and desire to secure by Letters Patent is:

1. An electric heater comprising a metallic shell, a refractory lining therefrom and a heating coil extended through said lining under maintained longitudinal tension and free from longitudinal obstruction in the lining. 85
2. An electric heater comprising a metallic shell, a refractory lining therefor, a heating coil in said lining, and an insulating bushing for each end of the shell having a screw thread fitting a corresponding thread on the shell with an external recess in its end and a polygonal depression in the bottom of the recess. 90
3. An insulating bushing for closing the end of an electric-heater shell provided with a screw thread and having on its outer end a recess in the bottom of which is a polygonal depression. 100
4. An insulating bushing for closing the end of an electric-heater shell containing a metallic block for connection with the heater coil, a recess at its outer end, a polygonal depression at the bottom of the recess, and a binding connector in said depression for connecting said block to the external circuit. 105
5. An insulating bushing for closing the end of an electric-heater shell containing a metallic block which has at its outer end a binding-screw hole with a countersink enlargement. 110
6. An insulating bushing for closing the end of an electric-heater shell having a recess at its outer end and a metallic block for the coil-connection having at the bottom of said recess a binding-screw hole with a countersunk enlargement. 115
7. An electric heater comprising a metallic shell, a tubular refractory lining fitting inside the shell, a heating coil extended through said lining, coil-terminals passing through insulation in the shell, and external insulation applied to the outside of said shell. 125
8. An electric heater comprising a metallic shell, a tubular refractory lining fitting the inside of said shell, a heating coil extend- 130

- ing through said shell, coil-terminals passing through insulation, and external, insulating supports secured to the shell.
9. An electric heater comprising a metallic shell, a refractory lining fitting the inside of the shell, a heating coil extending through said lining, coil-terminals extending through insulation in the shell, and an external block of insulation secured to said shell.
10. An electric heater comprising a tubular metallic shell, a refractory lining fitting the inside of the shell, a heating coil extending through said lining, insulated coil-terminals and an insulating support secured on each end of the tubular shell.
11. An electric heater comprising a shell in the form of a metal tube having ribs on its central portion and circular ends, a refractory tubular lining extending through said shell and fitting the interior thereof, a heating coil in said lining, coil-terminals passing through bushings on each end of the shell, and an external insulating support on each of the circular ends of the shell.
12. An electric heater comprising a metal shell having ribs on its central portion and circular screw-threaded ends, a refractory tubular lining fitting the inside of said shell, a heating coil in said lining coil-terminals extending through screw-threaded bushings in each end of the shell, and external insulation embracing and secured outside of each end of the shell.
13. The method of forming an electric heater which consists in securing a metal shell on a refractory tube contained therein, and threading a heating coil through said tube after it is in place in the shell.
14. The method of forming an electric heater which consists in securing a metal shell on a refractory tube contained therein, threading a heating coil with an attached terminal thereon through said refractory tube, and securing the said terminal in an insulating bushing in the farther end of said shell.
15. The method of forming an electric heater which consists in securing a refractory tube within a metallic shell, passing one end of a heating coil provided with an attached rigid terminal through said tube, and securing each terminal of said coil in an insulating bushing on the metallic shell.
16. The mode of forming an electric heater which consists in securing a refractory tube inside of a metallic shell, passing through said tube one end of a heating coil having a rigid terminal permanently secured to each of its ends, and securing the two rigid terminals successively in bushings at the respective ends of the shell.
17. The method of forming an electric heater which consists in securing a refractory tube inside of a metallic shell, passing through said refractory tube one end of a heating
- coil having a rigid screw-threaded terminal secured to each end, and successively screwing each of the said terminals into an insulating bushing at the end of the heater.
18. The mode of forming an electric heater which consists in pressing a metallic shell into its approximate shape, inserting therein a tubular lining of refractory material, compressing the metal shell around said lining, and then threading a heating coil through said lining and connecting its ends to suitable binding connectors.
19. The mode of forming an electric heater which consists in pressing a metal shell into the form of a tube with parallel ribs, inserting in the tubular part a perforated lining of refractory material, passing the shell between grooved pressing agents to draw the metal thereof securely around said lining and then passing the heating coil through the perforation of the lining.
20. As an article of manufacture, a metallic electric-heater shell of tubular form having a closely fitting refractory lining therein.
21. As an article of manufacture, a metallic electric-heater shell of tubular form having a closely fitting lining of refractory material therein.
22. As an article of manufacture, a metallic electric-heater shell having a refractory lining therein composed of tubular sections.
23. As an article of manufacture, a metallic electric-heater shell of tubular form having therein a refractory lining composed of tubular sections around which the metal of the shell is compressed.
24. As an article of manufacture, a metallic electric-heater shell of tubular form with ribs thereon and having a refractory lining therein composed of a series of tubular sections closely fitting the shell.
25. As an article of manufacture, a metallic electric-heater shell of tubular form with an integral rib thereon having a refractory lining therein composed of a series of tubular sections closely fitting the shell.
26. As an article of manufacture, a metallic electric-heater shell compressed into tubular form with an integral rib thereon and having therein a refractory lining closely fitting the shell and composed of a series of tubular sections.
27. As an article of manufacture, a metallic electric-heater shell formed by pressing a tube into a tube of smaller diameter with doubled integral flanges on both sides and having a closely fitting lining of refractory material.
28. As an article of manufacture, an electric-heater coil having rigid terminals permanently secured thereto and a predetermined length of wire between said terminals.
29. As an article of manufacture, an electric-heater coil having rigid screw-threaded

terminals permanently secured thereto and a predetermined length of wire between the said terminals.

30. As an article of manufacture, an electric-heater coil having rigid terminals permanently secured thereto having a maximum diameter not exceeding substantially the diameter of the coil with a predetermined length of wire between said terminals.

31. As an article of manufacture, an electric-heater coil having its ends swaged into rigid terminals between which is a predetermined length of wire.

32. As an article of manufacture, an electric-heater coil having at each end and permanently secured thereto a combined connection-terminal and marker with a predetermined length of wire between the two.

33. An electric-heater coil provided with a terminal having a helical groove into which the end of the coil is swaged.

34. The combination with a wire coil of a terminal therefor of substantially the diameter of the coil and having a helical groove therein into which the wire of the coil is threaded and swaged.

35. The combination with a wire coil of a terminal therefor of substantially the diameter of the coil and having an external groove forming a continuation of the coil helices into which the wire of the coil is threaded and swaged.

36. The combination with an electric-heater coil of a terminal therefor having an enlarged end to which the wire of the coil is secured and a reduced shank of limited heat-conducting capacity.

37. The combination with an electric-heater coil of a terminal therefor having an enlarged end to which the wire of the coil is secured and a reduced shank of limited heat conducting capacity on which are characters identifying the coil.

38. The combination with an electric-heater coil of a terminal permanently connected thereto on which are characters identifying the coil.

39. The combination with an electric-heater coil of terminals permanently secured thereto having a screw-threaded portion of reduced heat-conducting capacity.

40. An electric heater comprising a metallic shell, a refractory tubular lining therefor in close contact therewith, a heating coil in said lining, an insulated metallic block for connection to the external circuit, and a connector of reduced heat-conducting capacity between said block and the end of the coil.

41. An electric heater comprising a metallic shell, a tubular refractory lining closely fitting the shell, a heating coil in said lining, a metallic block insulated from the shell for receiving the external circuit con-

nection, and an elongated coil-terminal between the block and coil for restricting the transmission of heat from the coil to said block.

42. An electric heater comprising a 70 pressed metal shell of tubular ribbed form with circular ends, a closely fitting lining in said shell formed of tubular sections, an insulating bushing in each of said ends with an outer recess, a metallic block extending through said bushing from the bottom of said recess, a heating coil extending through the lining with an elongated terminal between the end of the coil and the said metallic block. 75

43. An electric heater comprising a metallic shell, a refractory tubular lining closely fitting the interior of said shell, an insulating bushing sealing the end of the shell, a separable heating coil extending through said lining, and a conductor larger than the wire of the coil passing through said bushing and sealed therein for connecting the coil with the external circuit. 80 85

44. An electric heater comprising a flexible metallic shell, a refractory lining therefor formed of tubular sections relatively shaped to permit the curvature of the shell, a tube secured to the end of the shell, a bushing in said tube, a heating coil in said lining, and a conductor passing through said bushing to connect the coil with the external circuit. 90 95

45. An electric heater comprising a metal tube, a refractory lining fitting the tube, a coil in said lining separable therefrom, coil-terminals of larger diameter than the wire of the coil, and an insulating bushing through which the said terminals are extended. 100 105

46. An electric heater comprising a metal tube, a refractory lining therefor, a heating coil in said lining separable therefrom, coil-terminals secured to the ends of the coil, and insulated metal blocks with which said terminals are separably connected for receiving the external-circuit wire. 110

47. An electric heater comprising a metal tube, a refractory lining therefor, a heating coil in said lining separable therefrom, an insulating bushing recessed externally, a coil-terminal connected to a metal block located in said bushing below the recess and a rigid connector extending outwardly from said block. 115 120

48. An electric heater comprising a tube or duct of refractory insulating material and a heating element therein consisting of a coil of resisting wire of such diameter with respect to the tube or duct as to slide freely therethrough. 125

49. An electric heater comprising a tube or duct of refractory insulation and a heater element consisting of a coil of resisting wire having a terminal attached thereto, both 130

- coil and terminal being of such diameter with respect to the tube or duct as to slide freely therethrough.
50. An electric heater containing a heating coil under tension and a fusible retainer therefor.
51. An electric heater comprising two or more component coils in the same heating circuit each provided with an individual 10 fuse.
52. An electric heater comprising an insulating duct of refractory material, a heating coil therein, and a fuse for the coil contained in the said duct.
- 15 53. An electric heater comprising a metal casing, a refractory lining therein, and a removable heating coil and fuse therefor within said lining.
- 20 54. An electric heater comprising an elastic heating coil under tension, a terminal for the coil and a retaining fuse between said terminal and a fixed part of the heater.
- 25 55. An electric heater comprising an elastic heating coil under tension, two members capable of sliding on each other one connected to the said coil, the other to a fixed part of the heater and a fusible retainer between said members.
- 30 56. An electric heater comprising a refractory insulating tube, an elastic heating coil therein under tension, a terminal attached to said coil and capable of longitudinal movement in said tube, and fusible retaining means for said terminal.
- 35 57. An electric heater comprising a refractory insulating container, an elastic heating coil in said container under tension and having free play therein, and fusible retaining means for said coil.
- 40 58. An electric heater comprising a refractory insulating container, an elastic heating coil in said container under tension, a two-part terminal for said coil, and a fusible retainer between the two parts.
59. An electric heater comprising a refractory insulating tube, an elastic heating coil thereon fitting the tube but having free play therein, means for holding said coil under tension and a fusible retainer for said means. 45
- 60 60. An electric heater comprising a refractory insulating container, an elastic heating coil therein held under tension, a terminal for said coil, a terminal extension of reduced heat-conducting capacity, and fusible retaining means between said terminal and its extension. 50
- 65 61. An electric heater comprising a duct of refractory insulating material, an extension of said duct containing an insulated block for the external circuit connection, an elastic heating coil in said duct free to pass longitudinally therein, and a terminal member between said coil and the said insulated block. 55
- 66 62. The method of forming an electric heater which consists in first placing in permanent position a refractory insulating tube, passing through said tube a heating coil of less diameter and securing the respective ends of the coil to insulated connection blocks. 60
- 70 63. The method of forming an electric heater which consists in placing a refractory insulating tube in its permanent position, threading through said tube an elastic, extensible heating coil, normally shorter than the tube, securing one end of said coil, drawing the opposite end out beyond the end of the tube, securing thereto a terminal block for connection with the external circuit and allowing the coil to rest in the tube in a condition of tension. 75
- 80 Signed at Albany, county of Albany, State of New York, this 20th day of January, 1922. 85

LEE P. HYNES.
